Oscar Geller

UNITED STATES PATENT OFFICE.

MAXIM M. BET, OF WEST MOOSE JAW, SASKATCHEWAN, CANADA.

WEAPON.

1,268,205.

Specification of Letters Patent. Patented June 4, 1918.

Application filed January 29, 1918. Serial No. 214,292.

To all whom it may concern:

Be it known that I, MAXIM M. BET, a citizen of Russia, resident of West Moose Jaw, Province of Saskatchewan, and Dominion of Canada, have invented certain new and useful Improvements in Weapons, of which the following is a specification.

This invention relates to improvements in weapons of types used in warfare and particularly to types in which are combined the elements of a gun using explosive cartridges and a blade used as a sword.

The principal object of the invention is to provide a weapon which may be conveniently carried and in which are combined two separate weapons so that either can be used when desired and without one interfering with the function of the other.

A further object is to provide an improved gun lock whereby rapidity of firing may be attained.

These and other like objects are attained by the novel construction and combination of parts hereinafter described and shown in the accompanying drawings; forming a material part of this specification, and in which:

Figure 1 is a side elevational view of a weapon made in accordance with the invention.

Fig. 2 is an enlarged fragmental side elevational view of the gun lock construction, the cover being removed in order to show the interior.

Fig. 3 is a fragmental side elevational and sectional view showing the operating mechanism.

Fig. 4 is a side elevational view looking from the other side of the weapon.

Fig. 5 is a transverse sectional view taken on line 5—5 of Fig. 4, and

Fig. 6 is a perspective view of the cylinder and its rotative means.

In the drawings the numeral 10 designates the blade or weapon, which may be made of any preferred size or style whatever. This blade is rigidly attached to a body casing 11, terminating in a curved hilt or handle 12. Pivoted to the casing 11, by the screw 14, is a guard lever 15 which is also used in discharging the cartridges, the guard being held normally extended by means of a coiled compression spring 16, surrounding a curved stem 17, fixed in the extreme end of the curved hilt

12, at one end and extending through an appropriate opening formed in the guard lever 15 at the other.

Secured alongside the blade 10 and extending from the casing 11, is a barrel 18, adjacent to the rear end of which is rotatably mounted a cartridge carrying cylinder 20, the same being journaled upon a pin 21, fixed in the casing 11, and contains a plurality of openings 22 for the cartridges 23, the same being of ordinary type.

A firing pin 25 is formed with a lever 26, pivoted upon the pin 27 contained within the body 11. Formed with the lever 26 is a projection 28, held normally upward by the bent flat spring 29, so that the point of the projection 28 is held normally in engagement with a star wheel 30, adapted, as it is rotated, to depress the projection and cause the lever 26 to oscillate. The star wheel is journaled on a spindle 32, on which is affixed a gear 33, the teeth of which are in engagement with a pinion 35, mounted on a spindle 36, carried in a bracket 38, all of the several parts being contained in the casing 11.

Also mounted on the spindle 36 is a disk 38, on one side of which, by the pin 40, is pivoted a link 41, the other end being pivoted by the pin 42 to a sliding bar 43 mounted to move longitudinally, the bar having at its outer end a transverse element 44, which carries a plunger 45, adapted to expel exploded cartridges from the cylinder 20.

Motion is communicated to the gear 33 by means of a ratchet wheel 48 secured on the spindle 32, the same being engageable with a pawl 49, formed at the end of an extension 50, of a lever 51, pivoted on the pin 52, set in the casing, the opposite end of the lever being pivotally engaged with a link 54, connected with the long arm 55 of a bell crank 56, the short arm of which has a link 58 pivotally engaged with the firing element or guard 15. Thus as the guard is pressed toward the hilt 12, the several disks are rotated, acting co-operatively to expel exploded cartridges, while at the same time the cartridge cylinder is rotated in the following manner.

The casing 11 has an extension in which is pivoted a pawl 59, having its curved inner side closely adjacent to the cylinder 20 and held firmly therein by means of a spring 60,

secured in the casing 11. The lower end of the pawl has a hook finger 62, engageable with which is a spur 65, secured to the upper side of the sliding bar 43, the arrangement being such that as the bar is moved toward the front, the pawl is caused to rise, liberating one of a plurality of pins 66 set in the periphery of the cylinder, so that the same may be rotated, the pins being normally held by the hook formed at the end of the pawl.

The spur 65, travels over the top of the hook finger 62, on its return transmitting no motion to it.

15 At the rear end of the cylinder 20, are a plurality of projecting pins 70, corresponding in number to the chambers of the cylinder, operated by engagement with the upper end of a sliding bar 72, when pushed upward by the flat spring 73, the hooked end 90, being held in contact with the pins by means of a spring 92, permitting the bar to move outward and clear the pins when moved downward by contact with a projection 74, formed on the lever 75, pivoted on a pin 76, at one end, and engaged with a link 77, at the other. The opposite end of the link 77 is drawn rearward by a slide 78, operated by a projection 79 of the lever 51, 30 which is operated through the guard 15.

In operation, cartridges are supplied by hand to the left hand side of the casing 11, and pressed into their respective openings 22 in the cylinder by means of a plunger 80, 35 extending from a yoke 81 with which is engaged a guide bar 82, movable in brackets 83 and 84 secured to the end of the yoke 81, and having a crank 86, connecting with the link 87 by a pin set in the opposite side of the 40 disk 38.

The cartridges are pushed into position by the guard 15, simultaneously with the displacement of the exploded cartridges from the opposite side of the cylinder.

45 When the guard 15 is depressed or lowered, with respect to the hilt 12, the cylinder is turned a proper amount to admit the entrance of a new cartridge therein.

From the foregoing it will be seen that an 50 effective device for loading and expelling cartridges, as well as rotating the cylinder, has been shown and described in such man-

ner that one familiar with the art can construct and operate the same.

Having thus described my invention, what 55 I claim as new and desire to secure by Letters Patent, is:—

1. In a small arm, the combination with a handle, a cylinder, a barrel, and a sword blade extending from said handle, of means 60 for ejecting spent cartridges simultaneously with the entrance of a fresh cartridge, means for rotating said cylinder and means for exploding a cartridge in said cylinder.

2. In a small arm, the combination with a 65 body having a cylinder rotatably mounted therein, a sword blade rigidly engaged with said body and a guard lever hingedly connected to said body, of means for expelling cartridges from said cylinder, means for rotating said cylinder and means for detonating 70 a cartridge in said cylinder.

3. In a gun mechanism, the combination with a body, a cylinder revolvably mounted therein, and a guard lever hingedly connected to said body, of means actuated by said guard lever for seating, expelling and detonating cartridges, means for rotating said cylinder and means for holding said cylinder when in operative position, all of said means 80 being actuated by said guard lever.

4. In a small arm, the combination with a body, having a fixed blade, and a fixed barrel, of a cylinder revolvably mounted in said body, a guard hingedly engaged with said body, said guard extending rearwardly coincident with the handle of said body, means for normally extending said guard, a gear train mounted in said body, said gear train being operated by said guard, means actuated by said gear train for seating cartridges to said cylinder, means for expelling spent cartridges coincidently with the entrance of fresh cartridges, means for rotating said cylinder actuated by said guard, means for locking said cylinder when in an operative position, and means for detonating a cartridge in said cylinder.

In testimony whereof I have affixed my signature.

MAXIM M. BET.

Witness:

J. W. CARMAN.
